UNITED STATES PATENT OFFICE

2,690,711

MECHANICAL IGNITER FOR SIGNALING DEVICES

Leonard D. Jackson, Alexandria, Va.

Application July 1, 1946, Serial No. 680,782

6 Claims. (Cl. 102—70)

(Granted under Title 35, U. S. Code (1952),
sec. 266)

1

This invention relates to a mechanical igniter and is particularly adapted for use on signalling devices such, for example, as a flare, smoke float or the like of the type adapted for use either on land or water.

The present invention provides a new and improved mechanical igniter which is adapted to be detachably secured to a signalling device thereby to ignite at will the pyrotechnic material arranged within the signalling device.

The present invention provides a new and improved igniter for a flare, smoke signal and the like having a predetermined time delay between the operation of the firing means and the starting of the pyrotechnic material arranged within the flare or smoke signal.

One of the objects of the invention is the provision of a new and improved igniter for a signalling device in which the firing pin of the igniter is retracted a predetermined amount before the firing pin is automatically released thereby to initiate firing of the pyrotechnic material contained therein.

Another object of the invention is the provision of an igniter for a signalling device in which new and improved means are provided for locking the firing mechanism thereof in a safe position thereby to prevent premature firing of the signalling device during handling and transportation.

A further object of the invention is to provide a new and improved igniter which is economical to manufacture, reliable in operation, and which possesses the qualities of durability and safety during handling and transportation.

Still other objects, novel features, and advantages will become apparent from the following specification, taken in connection with the accompanying drawings, wherein:

Fig. 1 is a view of a signalling device partly in section and partly in elevation and showing the igniter of the present invention secured thereto;

Fig. 2 is an enlarged sectional view of the igniter showing the parts thereof in a safe or unarmed position;

Fig. 3 is an enlarged fragmentary sectional view of the upper portion of the igniter casing showing the operating element and firing plunger thereof in elevation;

Fig. 4 is a view similar to Fig. 2 but showing the igniter in the armed position in full lines and also showing the firing position thereof in dashed lines;

Fig. 5 is an enlarged sectional view taken on line 5—5 of Fig. 2;

Fig. 6 is an enlarged sectional view taken on line 6—6 of Fig. 2; and

2

Fig. 7 is an enlarged sectional view taken on line 7—7 of Fig. 2.

Referring now to the drawings for a more complete understanding of the invention, the igniter disclosed thereon is generally indicated by the reference character 10 and is adapted to be secured to a signalling device 11 of any well known type. While on Fig. 1 of the drawing the igniter is shown in connection with a marine signalling device it will be understood, however, that the igniter is adapted for use with either a marine or land type signalling device, as the case may be.

The signalling device comprises an outer cylindrical casing 12 composed of sheet steel or of any other material suitable for the purpose. The casing 12 is provided with upper and lower walls 13 and 14 respectively, each wall having outwardly extending flanges 15 and 16 adapted to secure to the cylindrical casing 12 thereby to render the signalling device buoyant such that it is adapted to ride upon the surface of a body of water. Secured to the casing 12 in any suitable manner is a stabilizer indicated by the reference 18 comprising a cylindrical member 19 and end wall 21. The walls 19 and 21 are provided with a plurality of openings 22 thereby to admit water to the stabilizing chamber 23.

The walls 13, 14 and 21 are each provided with a centrally disposed opening 24 therein, each wall having outwardly extending flanges respectively surrounding each of the openings, the flanges are adapted to engage and support a tubular container 25. The container 25 is open at the upper end thereof thus providing means for filling the container with the pyrotechnic material 26 of any well known type such, for example, as a smoke, light or color producing mixture.

The usual meltable disc or partition 27 composed of zinc or the like is pressed into the upper end of the container 25, the cover being secured to the container by bolts 29. The cover is provided with a centrally disposed opening 31 surrounded by a flange 32 adapted to receive and support an internally threaded nipple 33.

The igniter of the present invention is attached to the nipple 33 in any suitable manner and comprises an elongated housing 34 having an enlarged head 35 extending above the cover 28, and a reduced tubular casing 36 integrally formed thereon and extending into a heat and pressure chamber 37 provided in the upper end of the container 25. The housing 34 is also provided with a threaded portion 38 adapted to engage the internally threaded nipple 33 thereby to support the igniter on the signalling device in operative rela-

tion with respect to the pyrotechnic material 26.

The head 35 is provided with oppositely arranged cutaway portions 39 adapted to receive a wrench or other tool suitable for the purpose, whereby the igniter may be screwed into the nipple 33. It will be understood, however, that a sealing gasket 41 is disposed between a shoulder 42 formed on the housing 34 and the nipple 33 thereby to maintain a moisture proof connection therebetween and prevent deterioration of the pyrotechnic mixture 26.

A quantity of starter mixture 43 is arranged within the lower end of the bore 40 between a normally sealed vent disc 44 secured within the bore, and a combustible end wall 45 secured to the end of the housing 34 in any suitable manner preferably by crimping or rolling the lower edge of the housing as indicated at 46, Figs. 2 and 4.

The vent disc 44 is composed of any material suitable for the purpose such, for example, as steel, brass or the like and comprises a body portion 47 having upper and lower flanges formed thereon and indicated by the reference character 48 and 49. The body portion 47 of the vent disc 44 is provided with a plurality of vent openings 51 normally sealed by any material suitable for the purpose such, for example, as a material known in the trade as "668 Starter" and indicated as at 52. The vent disc 44 is secured within the bore 40 in any suitable manner but preferably by having threaded engagement with the housing 34 as at 53. The flange 49 is provided with a plurality of slots 54 formed therein adapted to receive a wrench or any other tool suitable for the purpose for threading the vent disc 44 into the bore 40.

A tube 55 composed of any material suitable for the purpose such, for example, as aluminum, steel, brass or the like, is secured to the vent disc 44 in any suitable manner preferably by soldering or welding the parts together as indicated by the reference character 56, the tube being provided with a recess 57 in the upper end thereof for receiving and supporting a percussion cap 58 therein.

A time delay fuse 59 is arranged within the tube 55, the fuse having a short length of quickmatch 61 secured in the upper end thereof and spaced a predetermined distance from the percussion cap 58 such that ignition of the quickmatch will occur when the percussion cap is fired. The time delay fuse 59 passes through a centrally disposed opening 62 provided in the vent disc 44 and extends a predetermined distance into the starter mixture 43, and is provided with a length of quickmatch 63 mounted crosswise therein by reason of diametrically opposite slits provided in the lower end of the fuse. The quickmatch is maintained in position within the fuse by a length of string or the like indicated by the reference character 64.

The tube 55 is provided with a restricted bore 65 which communicates with the recess 57 therein, the bore 65 being arranged in such a manner with respect to the recess 57 in which the cap 58 is secured as to direct the flash therefrom when fired directly against the end of the quickmatch 61 thereby to fire the quickmatch and initiate ignition of the delay fuse 59. The tube 55 is also provided with a plurality of relief ports 66 adapted to permit the gases to escape therethrough thereby to reduce the pressure within the tube when the percussion cap 58 is fired and as the quickmatch and time delay fuse burns thus preventing violent explosion of the confined gases within the tube.

A threaded recess 67 is provided in the outer end of the head 35 of the housing 34 and is adapted to communicate with the bore 40.

An operating knob or handle generally indicated by the reference character 68 is detachably secured to the head 35 and comprises an enlarged serrated hand grip 69 connected to a flange member 71 by a neck portion 72. The flange member 69 has a reduced threaded nipple 73 formed thereon adapted to have threaded engagement with the recess 67 thereby to detachably secure the operating handle to the head and also to maintain the igniter in a safe or unarmed position, Figs. 2 and 3, during handling and transportation thereof. A shank 74 is integrally connected to the nipple 73 and extends a predetermined distance into the bore 40, the shank having a pair of spaced lugs 75 formed thereon, each lug being provided with cam surfaces 76, the purpose of which will be more fully described hereinafter.

A sealing gasket 78 composed of any material suitable for the purpose is disposed about the nipple 73 between the flange 71 on the operating knob, and the upper portion of the head 35 on the housing thus providing a moisture proof seal therebetween thereby preventing deterioration of the pyrotechnic materials contained within the housing 34.

A plunger 77 is slideably and rotatably arranged within the bore 40, the plunger comprising a fluted body 78, the upper end thereof being provided with a recess or cutaway portion 79, one wall thereof having a complementary cam surface 81 formed thereon and adapted to coat with the cam surface 76 on the lugs 75 thereby to release the plunger 77 from interlocking engagement with the knob when the knob 68 has been unscrewed from the head 35 and the plunger and knob have been moved a predetermined amount outwardly, Fig. 4. It will be understood, however, that when the plunger 77 has been moved to the position as shown on Fig. 4 of the drawings, the knob is disengaged and the plunger will be free to move inwardly and will be forced to a firing position by the spring 80 as also shown in dashed outline. The cam surface 76 on the lugs 75 are adapted to coat with the cam surface 81 on the plunger in such a manner as to permit release of the plunger from the knob when the plunger has been moved to an armed position due to the pressure applied to the plunger by the spring 80 and the cam action between the cam surfaces 76 and 81. The spring 80 surrounds the plunger and the respective ends thereof are in abutting engagement with a plurality of tabs 83 formed on the plunger and a shoulder 84 formed within the bore 40 of the housing 34.

The upper end portion of the plunger 77 is provided with a screw threaded bore 85 having threaded engagement with a firing pin 86, the firing pin being provided with the usual striker 87, Figs. 2 and 4. The plunger is also provided with a centrally disposed opening or bore 88 extending therethrough into which the tube 55 extends thereby to provide a guide for the plunger 77 during the sliding and rotative movement thereof to an armed position.

It will be understood, however, that when the igniter 10 is desired to be fired the operating knob 68 will be grasped by the operator and rotated a predetermined number of revolutions and, due to the interlocking engagement between the plunger and knob, the rotation thereof will be mutual until the threaded nipple 73 has become disengaged from the recess 67 in the housing 34.

When this occurs a direct outward pull is applied to the operating knob 68 by the operator whereupon sliding movement is imparted to the plunger and the spring 80 is additionally contracted between the tabs 83 and shoulder 84. After the operating handle 68 has been moved a predetermined amount by the operator, the lugs 75 will become disengaged from the recess 79 in the plunger due to the pressure exerted on the plunger by the spring 80 and the action between the cam surfaces on the plunger and operating handle thereby releasing the plunger.

When the plunger is released, continued action of the spring 80 will urge the plunger to a firing position as shown in dashed outline, Fig. 4, with the striker 87 of the firing pin in operative engagement with the percussion cap 58 thus igniting the quickmatch 61 mounted in the upper end of the time fuse 59 thereby to cause firing of the time delay fuse 61. After a predetermined period of time controlled by the time fuse has elapsed, the quickmatch 63 secured in the lower end of the fuse will be ignited thereby causing ignition of the starter mixture 43. As the starter mixture 43 burns, the heat generated therefrom will melt the material 52 which seals the openings 51 in the vent disc 44 thereby unsealing the openings 51 and allowing the gases generated by the burning mixture to escape therethrough into the bore 40 above the disc. It will be understood, however, that the plunger 77 is provided with a plurality of fluted or grooved portions 92, Figs. 5, 6, and 7, to allow the free passage of gases through the bore 40 in the housing 34 to the atmosphere, thus preventing a violent explosion from the confined gases within the housing during the burning of the starter mixture.

As the starter mixture 43 continues to burn, heat and pressure generated therefrom will be sufficient to cause disintegration of the combustible end wall 45 thereby allowing the hot slag produced by the burning of the starter mixture to escape through the now open end of the housing 34 and fall upon the zinc disc 27 causing disintegration of the disc and ignition of the pyrotechnic material 26. Sufficient heat and pressure are now stored within the heat and pressure chamber 37 to melt the solder surrounding the usual sealing disc 89 on the container 25 thereby allowing the pressure within the chamber to blow off the disc 89 and unseal the usual exhaust ports 91 so that the smoke or light, as the case may be, produced by the burning of the pyrotechnic mixture 26 will escape through the ports 91.

The many advantages of the igniter constructed in accordance with the present invention will be readily apparent to those skilled in the art from a consideration of the foregoing description and drawings, and although a preferred embodiment of the device is illustrated and described, it is to be understood that changes in the details of construction and in the combination and arrangement of parts may be resorted to which fall within the scope of the invention as claimed.

The invention disclosed and claimed herein may be manufactured and used by or for the Government of the United States of America for governmental purposes without the payment of any royalties thereon or therefor.

What is claimed as new and desired to be secured by Letters Patent of the United States is:

1. An igniter for a signalling device of the class described comprising a housing having a quantity of starter mixture arranged therein, igniter means arranged within said housing and adapted

to ignite said starter mixture, releasable firing means rotatably and slideably arranged within said housing and adapted to be rotated a predetermined amount and slideably moved to an armed position, means detachably secured to said housing and releasably connected to said firing means for actuating the firing means to said armed position as the firing means is detached from said housing, means on said actuating means and including a gasket for hermetically sealing the housing until the actuating means is detached therefrom, resilient means operatively connected to said firing means for urging the firing means from said armed position to a firing position as the firing means is released thereby to fire the igniter means, a pair of complementary inclined cam surfaces arranged on the firing means and the actuating means respectively for releasing said firing means as the actuating means is disengaged from the housing, means attached to said housing for supporting said firing means slideably thereon and said igniter means therein, said supporting means having a plurality of ports therein for allowing the escape of gases therethrough as the igniter means is fired, and means for attaching said supporting means to said housing and having a plurality of sealed ports therein, said ports being adapted to be unsealed by the heat from the starter mixture as the mixture burns thereby to relieve the gas pressure within the housing.

2. An igniter for a signalling device of the class described comprising a housing having a quantity of starter mixture arranged therein, a disc arranged within said housing and having a tube secured thereto, a percussion cap arranged within said tube, igniter means arranged within said tube and adapted to ignite said starter mixture, said tube having a plurality of openings arranged therein for venting the tube as the igniter means is fired, releasable firing means arranged about said tube and adapted to be moved rotatably and slidably to an armed position, means detachably secured to said housing and releasably connected to said firing means for moving the firing means to said armed position and adapted to release the firing means when moved a predetermined amount, means on said detachable means and in abutting relation with respect to said housing for hermetically sealing the housing, and a resilient member surrounding said firing means for urging said firing means from said armed position to a firing position as the firing means is released thereby to fire said igniter means, and means for releasing said firing means.

3. In an igniter for a signalling device, in combination, a casing for said signalling device, an inner container supported by said casing and having a quantity of pyrotechnic material arranged therein, a closure for hermetically sealing said container thereby to form a heat and pressure chamber therein, a housing supported by said closure, a disc disposed within said housing and secured thereto by threaded engagement therewith, a tube secured to said disc in axial alignment therewith, igniter means arranged within said tube and disc, firing means arranged about said tube and within said housing and adapted to be moved slideably and rotatably to an armed position, means detachably secured to said housing and releasably connected to said firing means for actuating the firing means to said armed position, means on said actuating means for releasing the firing means as the actuating means is detached from said housing, re-

silient means operatively connected to said firing means and adapted to urge said firing means from said armed position to a firing position thereby to fire said igniter means and ignite said pyrotechnic material as the firing means is released, port means in said tube for venting the tube as said igniter means is fired, and a plurality of sealed exhaust devices in said inner container in communication with said heat and pressure chamber and adapted to be unsealed by said heat and pressure as the pyrotechnic material burns thereby to permit the escape of the products of combustion of the pyrotechnic material.

4. An igniter for a signalling device comprising a housing having a quantity of starter mixture arranged therein, an annular disc secured within said housing adjacent the starting mixture, a tube secured to said disc in axial alignment therewith, igniter means arranged within said tube and said disc, a plunger slideably and rotatably arranged about said tube and within said housing, a firing pin secured within said plunger, a spring surrounding said plunger and in engagement therewith for actuating said plunger, an actuating member rotatably and detachably secured to said housing and releasably connected to said plunger, a hand grip on said actuating member for moving the actuating member sufficiently to release said plunger against the force of said spring when a predetermined force is applied to said hand grip after the actuating member has been rotated sufficiently to be detached from the housing, said igniter means including a percussion cap adapted to be fired by said firing pin as the plunger is released by said actuating member thereby to ignite said starter mixture, and said disc having a plurality of openings arranged therein, melttable means for sealing said openings until the starter mixture burns thereby to prevent premature deterioration of the starting mixture and permit the escape of gases therethrough as the starting mixture burns.

5. An igniter for a signalling device of the class described comprising a housing having a quantity of starter mixture disposed therein, an annular disc arranged within said housing adjacent the starter mixture and having a tube secured thereto in axial alignment therewith, a time delay fuse arranged within said tube and said disc and adapted to fire said starter mixture, a percussion cap secured within said tube and adapted to ignite the time delay fuse, a normally locked

fluted plunger slideably and rotatably arranged about the tube, a firing pin secured to the plunger, actuating means in threaded engagement with said housing and detachably secured thereto and to the plunger for normally locking the plunger in an initial safe position, means on said actuating means for moving the plunger from said initial safe position to an unlocked position and thereafter releasing the plunger when the actuating means and plunger have rotated sufficiently to disengage the actuating means from the housing, and a resilient member on said plunger for urging the firing pin into firing engagement with the percussion cap as the plunger is released.

15 6. An igniter for a signaling device of the class described comprising a casing, a quantity of starter mixture disposed within the casing, a disc secured to said casing adjacent the starter mixture for preventing deterioration of said starter mixture, a tube secured to said disc in axial alignment therewith, a percussion cap secured within the tube, said tube having a plurality of apertures therein for venting the tube as said percussion cap is fired, a time delay fuse arranged within said tube and the disc for firing said starter mixture in time delayed relation with respect to the firing of said percussion cap, a plurality of sealed ports in said disc and adapted to be unsealed by the heat and pressure from the starter mixture as the mixture is ignited and burns thereby to permit the escape of gases therethrough, a normally locked spring actuated plunger slideably and rotatably disposed about the tube for movement into firing engagement with the percussion cap when unlocked, and means including an actuating member in threaded engagement with the casing and detachably secured thereto and to the plunger for unlocking and releasing the plunger to said firing engagement with the cap when said actuating member has been rotated sufficiently to be disengaged from the casing and a predetermined force applied thereto.
